HOOP WORK HOLDER

Harlow Klema and Clifford L. Qualler, Racine,
Wis., assignors to George Gorton Machine Co.,
Racine, Wis., a corporation of Wisconsin

Application July 30, 1951, Serial No. 239,258

2 Claims. (Cl. 112—102)

1

This invention relates to hoop work holders particularly adaptable for use in the positive supporting of hoops to be used for holding fabrics upon which stitching is to be carried out in the forming of monograms and other work of like characteristics.

The invention provides a device which has been ingeniously designed for the supporting of various sized hoops used in conjunction with a pantograph for embroidering, brocading, stitching or sewing by a controlled method. The design of the holder is such that a positive or fixed center point and position for mounting, is at all times maintained in relation to the pantograph mechanism regardless of the diameter of the hoop and in either an open or closed position. The maintaining of an established center is necessary to provide center area of the work with area of the pattern, be it character stitching or straight line sewing. The peculiar design of the holder further embodies the principle of carrying the material in positive relationship to the working pattern without swinging, arcing or uncontrollable, undesirable motion that would otherwise destroy the purpose of its function.

An object of this invention is to provide a hoop work holder, simple and rigid in design and operation, economical to manufacture and so constructed that any play or excessive back lash caused by wear will be automatically taken up and balanced out as the unit closes in on the hoops.

Another object of this invention is to provide a hoop work holder having a pair of oppositely disposed claw-type projecting clamping fingers for engaging a hoop actuated by a knurled thumb wheel mounted on a right and left hand screw whereby by turning the thumb wheel the fingers may be moved toward or away from each other while maintaining a constant center line for the respective sized hoop.

A further object of this invention is to provide a hoop work holder having a pair of mating gears, one of each being mounted at adjacent ends of the clamping fingers and when the thumb wheel is actuated the fingers will be supported and controlled in open or closed position without side swinging and maintaining the constant center point.

Still another object of this invention is to provide a hoop work holder having a lead screw of right and left hand threads with a thumb wheel mounted on its approximate center, the lead screw being easily detached from the holder whereby another screw having a different pitch

2

or lead may be readily substituted so that the clamping fingers may have an increased or decreased operating action with clamping action of greater or less power.

5 A still further object of this invention is to provide a hoop work holder to be used in conjunction with a pantograph mechanism for the forming of monograms or work having like characteristics, by sewing and having a simple control element which enables an operator of such equipment to maintain an easy sitting position without rising to change hoop sizes and to change hoops from one piece of work to the other. The device is so simple in design and so easy to manipulate, that operator fatigue is virtually eliminated. Its simplicity and adaptability to the purposes intended, further promotes production and confidence in use, and practically no maintenance is required.

10 With the foregoing general objects, and certain other objects, features and results in view which will be readily recognized from the following detailed description and explanation, our invention consists in certain novel features in design and construction, and in combinations and sub-combinations of parts and components, making up a mechanism of the invention, as will be more fully and particularly referred to in and specified hereinafter.

15 Referring to the accompanying drawings in which similar reference characters refer to corresponding parts throughout the several figures thereof:

20 Figure 1 is a view in top plan of a hoop work holder partly in section embodying our invention;

25 Figure 2 is a side view of the hoop holder of Figure 1 but on a smaller scale and partially in section;

30 Figure 3 is a view in top plan of a pantograph mechanism of the parallelogram form which is used for actuating the work holder.

35 Figure 4 is a view in rear elevation of one form of a pantograph mechanism and associated mechanism in operative relationship with the hoop or work holder.

40 The hoop work holder designated generally by the character F comprises a mounting bracket 10 of such material able to support, mount and control hoops which support a piece of fabric on which a monogram or other work of like characteristics is to be carried out. The left hand of bracket 10 is drilled at 11, with a slot 13 cut clear through from the hole 11 to one side of 45 50 55 the bracket. A hole 14 is formed from the end

of the bracket and a second hole 14a in line with hole 14 is formed beyond slot 13. The hole 14a is threaded whereby any suitable fastening element 15 may be inserted into hole 14 with the head 16 of the fastening element resting within a counterbored section 17 of the hole 14 and the threaded end 18 of the fastening element threadedly engaging the hole 14a. The function of the hole 11 is for mounting on a pin 64 (see Figure 4), which forms part of the pantograph mechanism, purposes of which will be described later.

The right hand of the bracket supports two equally spaced and in line pins or pivot studs 19 which project upwardly a substantial distance from the flat surface 20 of the bracket 10.

A pair of spaced clamping fingers 21 substantially yoke shaped at one end are connected to the bracket 10 through the medium of mating engaging gears 22 said gears having a cover 22a (see Figure 4). Each gear is fixed onto one end of its respective finger in a rigid position and is mounted on the pivot stud 19 as shown in Figure 2. The fingers may then swing toward or away from each other as the mating gears rotate on their respective pivot studs. The clamping fingers are perforated inwardly at 23. These perforations are spaced an equal distance from the mating gears 22 and from the inside edge 24 of each of the clamping fingers. The function of each perforation 23 is to support the shank 25 of a nut 26. The head 27 of each nut is approximately centrally apertured at 28 at right angles to the shank 25 and threaded. Incidentally, each of the shanks 25 are freely held in their respective perforation 23, whereby each may be readily detached from engagement therefrom. A thumb wheel 29 which is knurled or serrated on its outside edge, is centrally mounted on a shaft 30. One end of the shaft 30 is provided with right hand threads and the other end with left hand threads. In assembled state, one end of the shaft is threadedly mounted in one of the nuts 26 and the other end of the shaft is threadedly mounted in the other nut 26. Rotation, on one direction, of the thumb wheel 29, will spread the clamping fingers apart, while rotation of the thumb wheel in another direction, will swing the clamping fingers toward each other.

The free end 31 of each clamping finger is curved and is channeled at 32 on its inside surface 32a to support hoops to be of such design to incorporate sufficient rigidity along with lightness for the avoidance of drag and sluggish action. This inside surface 32a is formed in contours as indicated by the numerals 33 and 34 whereby, regardless of the size of various hoops, for instance, hoops having a diameter range of 4" to 10", each hoop will be securely held and each will have the same center point as indicated at 35 when clamped between the clamping finger. Each channel 32 along the surface 32a is provided with a resilient cushion of rubber 70, neoprene or any other suitable material against which a portion of the outside surface of the hoop may bear.

There are times when it becomes convenient to use a small size hoop, such as hoops having a diameter of 2" to 3". Therefore, to still maintain the common center point at 35, the applicants have devised removable bracket adapters for the proper positioning of such small hoops.

A pair of spaced holes 36 are drilled from the surface 32a clear through each finger to its outer edge 37. Each of these holes are spaced the same

distance from the free ends of each clamping finger and of such size to readily receive a dowel pin 38, one each of which are mounted on the ends of the bracket adapter designated by the numeral 39.

Each adapter is of the same size and has its inner surface 40 curved and also channeled whereby hoops of a range of 2" to 3" in diameter may be firmly gripped between the co-acting pair of curved surfaces 40. These adapters are readily attached or detached from the clamping fingers. While each dowel pin 38 is freely supported in their respective hole 36, nevertheless, each dowel pin slides easily in or out of the hole 36.

We have shown, for purposes of description only in the present application, the mechanism in Figures 3 and 4 which show generally, particular mechanism used with the hoop work holder of Figures 1 and 2.

The character P designates an adjustable pantograph unit of parallelogram form for movement transmitting operation by any well known tracer arm T carrying the usual tracer or styles movable over a pattern which may be commonly associated or mounted on a pattern table 41.

The work holder F of Figures 1 and 2 is operatively connected with the pantograph unit P.

A working element or tool in the form of a vertically disposed needle N is positioned above work holder F for movements of that work holder relative to the needle. The needle N forms a part of and may be taken to exemplify any conventional or adaptable type or form of sewing machine, hence it is not considered necessary to illustrate such a sewing machine.

The pantograph unit P and the sewing machine represented by the needle N, may be suitably mounted and arranged on a supporting structure which provides a horizontally disposed base or bed 42 above which there is mounted and supported in parallel, vertically spaced relation a horizontally disposed platform or work table 43.

The pattern table 41 is in the form of a rectangular platelike structure which is mounted and supported in horizontally disposed position on bed or base 42 between that base and the platform table 43 thereabove.

A minimum friction mounting arrangement for pattern table 41 is provided by which the pattern table is constrained precisely to its straight line path of movements in the horizontal plane parallel with bed 42 and work table 43 thereabove. In this example, such minimum friction mounting of pattern table 41 on bed 42 is effected by providing parallel channel structures or tracks 44 fixed to bed 42 along opposite sides thereof, respectively. Parallel guide strips 45 are secured in fixed position on and along and depending from the under side of pattern table 41. Guides 45 extend down into and are slideably received in channels 44, respectively, for reciprocation longitudinally therethrough. Series of anti-friction balls 46 are engaged between the adjacent side wall surfaces at opposite sides of channels 44 and guides 45 for rolling, minimum friction engagement therewith. Thus, pattern table 41 may be moved or slide inwardly or outwardly relative to bed 42 and work table 43 with minimum friction and by the application thereto of light forces.

The pantograph P includes a short bar 47 normally disposed generally transversely of pattern table 41 and being pivotally coupled at one end to the adjacent end of a long bar 48 and at its opposite end to the adjacent end of a link 49 parallel

with long bar 48. The pantograph P is completed by a link 59 which is pivotally associated at its opposite ends with adjacent rear ends, respectively, of long bar 48 and link 49. The primary pivotal support of the parallelogram linkage 47-48-49-59 of the pantograph unit P, is effected through the mechanism of pivot block 51. As none of this structure forms the present invention, the application merely points out the above structure as showing its use with the present invention.

The work holder F is connected with the pantograph P through a suitable linkage which though it is not a part of our present invention, a portion is illustrated herein and designated by the character L.

The linkage L includes a supporting bracket 53 secured to the base 42 at the rear left hand portion thereof when facing Figure 3. Supporting bracket 53 extends vertically upwardly from base 42 beneath work table 43, and a pair of parallel bars or links 54 and 55 are pivotally connected at their rear ends by pivots 54a and 55a, with the upper side of supporting block 53 in positions extending horizontally forwardly and outwardly in a direction away from the pantograph unit P and toward the adjacent left hand side of the work table 43. At their forward ends these parallel links 54 and 55 are pivotally connected by pivots 54b and 55b to one leg 56 of a bell crank lever 57 which is mounted in horizontally disposed position. Thus, the links 54 and 55, bell crank leg 56 and supporting block 53 form a single parallelogram linkage.

The link 54 is also pivotally connected at its forward end to the outer horizontally disposed beam 58 which is located generally transversely of links 54 and 55 and which terminates at its inner end adjacent but spaced to the rear of the outer end of pantograph link 50. A beam 59, similar to beam 58 is positioned generally parallel with but spaced forwardly from beam 58 and is pivotally mounted or swiveled at its inner end on stud 52. The outer end of beam 59 is pivotally coupled to the other leg 60 of the bell crank 57 by a pivot 59a this bell crank being positioned with leg 56, generally parallel with beams 58 and 59 and with legs 60 thereof transverse to such beams.

An L-shaped bracket member 61 provides a long arm 62 and a short arm 63. The forward end of short arm 63 of bracket 61 is pivotally mounted or swiveled on stud 52 in position above the end of beam 59 which is also mounted on stud 52. This short arm extends rearwardly from stud 52 generally transverse to beams 58 and 59, and at its rear end or junction with the inner end of long arm 62, has pivotally coupled thereto by shaft 64a the inner end of beam 58.

The long arm 62 of the L-shaped bracket member 61 extends outwardly in general parallelism with link 50 of pantograph unit P when the latter is in the squared position of Figure 3, and includes at its outer, free end an integral, upstanding split flange member 63a. The shaft 64 is secured firmly at one end in the split flange member 63 and extends vertically upwardly therefrom. The upper end of shaft 64 mounts the bracket member 10 which extends horizontally inwardly therefrom. The hoop work holder is mounted in horizontally disposed position by bracket member 10 on shaft 64, by inserting the shaft 64 in the hole 11 and threading the fastening member 15 in the threaded hole 14a and thus lessening the size of the slot 13 and the hole 11 whereby the bracket 10 is caused to be held firmly on the shaft 64. The 75

work table 43 is formed with an opening 65 therethrough above and around the free end of long arm 62 of bracket 61, through which opening shaft 64 extends to the upper side of the table. 5 Opening 65 is of sufficient area to permit of the full range of movements of shaft 64 by the bracket member in the operation of the linkage L by the pantograph unit.

The hoop work holder F is positioned by its 10 bracket 10 on shaft 64 to lie below the needle N of a sewing machine. This hoop work holder F is in position for universal lateral movement beneath and across needle N for sewing or embroidering operations as will be readily understood by 15 those familiar with such art.

Thus, it will be apparent that the linkage L connected as described will transmit movements to the hoop work holder to move that holder in a horizontal plane beneath and across needle N.

20 The pantograph mechanism has been disclosed in operative connection with the associated linkage L for operating the fabric mounting work holder F of our present invention, primarily for the purpose of giving an illustration of a mechanism which can be used to operate the work holder of the present invention. However, it is not intended by the illustrated example to limit the use of the work holder mechanism to association with any particular mechanism or organization to be 25 actuated therefrom, as the work holder of the invention is intended for use in any association or 30 for any purpose for which it may be adapted.

It is also evident that various modifications, substitutions, eliminations and additions may be 35 resorted to without departing from the broad spirit and scope of our invention, and hence, we do not desire or intend to limit the invention in all respects to the exact disclosures of the specific example thereof herein presented, except as may be required by specific, intended limitations thereto in certain of the claims hereto appended.

What we claim is:

1. In a work holder, the combination of a 40 bracket, a pair of clamping fingers having contoured work engaging surfaces, said bracket having a substantially flat base, a substantial portion of which is cut out at one end, said clamping fingers each provided with a yoked extension at similar ends with said cut out end received between said yoked ends, the base of said bracket and said clamping fingers lying in substantially the same plane said fingers rotatably mounted on said bracket, each of said fingers having a gear arranged to mate with each other, a support 45 mounted on each of said fingers and connected by a right and left hand threaded shaft, a thumb wheel mounted on said shaft between said supports, said gears, thumb wheel and clamping fingers so arranged whereby the center point respectively between said gears, said thumb wheel and said clamping fingers are in a straight line.

2. In a work holder, the combination of a 50 bracket and a pair of clamping members, said bracket provided with spaced apertures adjacent one end, a pin mounted in each aperture and secured therein, the free ends of each pin extending beyond each side of said bracket, similar ends of each clamping member having an apertured yoke like extension, each of said extensions having a portion of said bracket end disposed between said yoked ends with each of said yoked ends mounted on the free ends of said pins, a pair of mating gears rotatably mounted on similar 55 free ends of said pins, each of said gears rigidly mounted on one of said clamping members, each 60

of said clamping members rotatably mounted on one of said pins each of said clamping members having an aperture in which a headed dowel member is secured, each head drilled and threaded and mounting an oppositely threaded end of a shaft disposed between said heads, a wheel mounted on said shaft between said heads and arranged to rotate said shaft, rotation of said shaft causing rotation of said mating gears to swing said clamping members, said mating gears, wheel and clamping members so arranged whereby the center point between said gears, wheel and clamping members are in a straight line.
